UNITED STATES PATENT OFFICE.

THOMAS M. DENHAM, OF NEW BEDFORD, MASSACHUSETTS.

SHIRT.

SPECIFICATION forming part of Letters Patent No. 250,792, dated December 13, 1881.

Application filed October 17, 1881. (No model.)

To all whom it may concern:

Be it known that I, THOMAS M. DENHAM, of New Bedford, in the county of Bristol and State of Massachusetts, have invented certain new and useful Improvements in the Manner of Attaching a Shirt-Bosom to the Shirt; and I do hereby declare that the following is a full, clear, and exact description thereof, reference being had to the accompanying drawings, and to the letters of reference marked thereon, which form part of this specification.

My invention is an improvement in the manner of attaching the shirt-bosom to the front or body of the shirt, so that the bosom itself shall form an ellipse at its lower part, to open and shut with the motion of the body, the upper part, where exposed to view, maintaining its perfect and smooth appearance. By reference to patent granted me, dated August 26, 1873, No. 142,212, it will be seen the ellipse below is formed by attaching the shirt-bosom to the front of the shirt without cutting out any portion of the body-front. The lower portion of the bosom forms the front or outer part of the ellipse, the body of the shirt the back or inner side. By experience I find that where the muslin of the shirt-body is made of very fine threaded and closely woven material the bosom cannot be made so stiff, and requires more labor to starch. To obviate this complaint I propose to cut out a piece from the body of the shirt and fill in its place with a coarse material. I claim nothing new in making the bosom with coarse linings or backing, these being used for years, because they easily absorb and hold starch. My invention is in reality a spring or elliptic bosom joined to the shirt-body in sections, at different places, at the lower part of the bosom. I propose to make the bosom of two or more thicknesses, the back thickness to be of coarse material, completely filling in a space made in the body of the shirt of about the size of the bosom, the remaining thickness or thicknesses to be joined to the body or front, as shown by the annexed drawings.

In Fig. 2, D represents the body of the shirt and the bosom stitched thereto on lines A to A

and B to B on the sides, and from N to N at the bottom, thus leaving that portion of the bosom unstitched either to the body or back thickness from A to N and from B to N, as shown by dotted lines. This unstitched section across the lower part of the bosom, when raised or separated after ironing, will form the ellipse or weaker part below the vest-opening, to bend more or less as the body of the wearer is more or less bent or stooping, and resuming its original shape or smoothness when returning to an erect or standing position.

In Fig. 1, M shows the back lining of the bosom stitched the whole length of its sides to the body D, from F to S and L to X, and across the bottom from S to X, the bosom to be made of two or more thicknesses, according to the number of plaits in it. Thus a bosom with only one plait in the center would require more than one thickness, while a bosom with three wide plaits, or the whole width made up with plaits, would require no thickness other than the one back lining, which fills the space cut out of the body. This way of setting in the bosom while retaining the ellipse is, I believe, a decided improvement on my old patent of 1873.

What I claim as my improvement is—
In combination with a shirt, a front or bosom composed of two or more thicknesses of fabric, the back thickness being inserted in a space or cut-out portion of the body fabric and stitched at all points, and the front thickness being united at the sides from A to B and at the bottom from N to N, leaving its lower portion unattached at the sides from A to N, so as to form an ellipse and spring-hinge, substantially as described and shown, and for the purpose specified.

In testimony that I claim the foregoing as my own invention, I affix my signature in presence of two witnesses.

THOMAS M. DENHAM. [L. S.]
